[57] CLAIM

I claim the ornamental design for fanciful container with cap and bow, as shown and described.

DESCRIPTION

FIG. 1 is a top/front perspective view of a fanciful container with cap and bow;

FIG. 2 is a front elevational view thereof;

FIG. 3 is a rear elevational view thereof;

FIG. 4 is a side elevational view, the other side being a mirror image thereof;

FIG. 5 is a top plan view thereof;

FIG. 6 is a bottom plan view thereof;

FIG. 7 illustrates the container of FIG. 2 with the cap separated therefrom;

FIG. 8 illustrates the container of FIG. 2 without a cap; and, FIG. 9 is a perspective view of an alternate embodiment of FIG. 1, the difference being in the bow.
